BOTTLING ART

Application filed August 15, 1927, Serial No. 213,044. Renewed December 6, 1930.

My invention relates to bottles for containing various kinds of beverages, particularly carbonated or effervescent beverages, the bottle being usually closed with a sheet metal crown extending across the mouth of the bottle and crimped to a "locking ring" formed around said mouth, the crown comprising a gasket of cork or similar yielding or elastic material and the crown being afterward removed by bending the flange of the crown outward with a suitable tool. On the neck of such bottles there is just below the "locking ring" an outward extended, circumferential enlargement or thickening of the glass which reinforces the neck of the bottle and serves as a "holding ring" with which engagement may be made by parts of machines used for holding and lifting and carrying the bottle during various stages of manufacture of the bottle and during preparation of the bottle for its filling and during its filling and crowning.

Because these bottles are made and filled in very large numbers, the use of automatic mechanism in making and filling and crowning the bottles is necessary for the sake of economy, and to facilitate the use of such mechanism it is essential that the bottles be made of uniform shapes and dimensions. Such bottles now in use are inconvenient for drinking. If it is attempted to drink directly from the bottle, it is difficult to so apply the mouth of the bottle to the mouth of the person as to permit inflow of air during outflow of the beverage. That is because what is then the upper part of the lip of the bottle will press against the upper lip of the drinker. To avoid this, some persons tilt the head back. That is an inconvenient, and for some people impossible, position for swallowing liquids. Some drinkers put the entire upper end of the bottle into the mouth and then tilt the bottle and try to take the liquid with intervals for the admission of

air into the bottle. At times that method leads to strangling.

In such bottles now in use, the "locking ring" and the "holding ring" and the groove between those rings are parallel to each other and horizontal or in planes to which the axial line of the body of the bottle is perpendicular. 50

The object of my invention is to produce such a bottle in a form adapted for easy drinking—in a manner similar to drinking from a drinking glass, and such form being, at the same time, adapted to manufacture and filling and crowning by machines and methods now in use. 55

In the accompanying drawings, 60

Fig. 1 is an elevation of a bottle embodying my improvement, a part of the bottle being broken away;

Fig. 2 is a plan of the upper end of the bottle shown by Fig. 1; 65

Fig. 3 is an elevation of the upper part of the bottle as it appears looking at Fig. 1 from the right;

Fig. 4 is a view looking at the mouth of the bottle downward in the direction of the arrow above Fig. 1; 70

Fig. 5 is an upright section on the line, $\alpha-\alpha$, of Fig. 3, that line being in the plane in which lies the axial line of the body of the bottle; 75

Fig. 6 shows the upper end of the bottle in the position of Fig. 1, with a crown being applied to the locking ring;

Fig. 7 is an enlarged view of the upper end of the bottle as shown in Fig. 5, a crown having been applied; 80

Fig. 8 illustrates the upper part of the bottle in position for drinking;

Fig. 9 is a sectional elevation of the upper end of a bottle of the form now in general use, the locking ring and the holding ring being parallel to each other and horizontal or in planes to which the axial line of the bottle is perpendicular; 85

Fig. 10 is a detail sectional view showing 90

the crown being applied to the locking ring of a bottle of the form now in general use.

For convenience in description, the bottle will be regarded as being in the upright position, the base of the bottle being the lower end and the neck and mouth of the bottle being the upper end.

Referring to the drawings, A is the body of the bottle. B is the neck of the bottle. C is the holding ring. D is the locking ring. E is the crown. E¹ is the crimped flange of the crown. F is the die by means of which the flange of the crown is pressed downward over the locking ring, D (Fig. 6).

G and H are, respectively, the "holding ring" and the "locking ring" of the form of bottle now in general use (Figs. 9 and 10). As shown by these two drawings, these two rings are horizontal or in planes to which the axial line of the bottle is perpendicular. E is the usual circular sheet metal crown placed on the ordinary bottle. I¹ is the crimped flange of said crown. F is the die by means of which said crown is pressed into position (Fig. 10). In common practice, the die, F, moves downward with its axial line coinciding substantially with the axial line of the locking ring, H, of the bottle, that axial line coinciding substantially with the axial line of the body of the bottle. Thus the die surrounds the axial line of the bottle and moves downward parallel to that line.

Referring now to Figs. 1 to 8, inclusive, the lower part of the holding ring, C, is horizontal and positioned the same as in Figs. 9 and 10. But the locking ring, D, is placed slantwise, at an angle of approximately 20 degrees from the horizontal, the higher part being at the height of the locking ring, H, in Fig. 9. This brings the lower part of the locking ring, D, closer to the lower part of the holding ring, C, as shown in Figs. 1, 3 and 5. All parts of the exterior or outside lateral face of the locking ring are equi-distant from the axial line of the bottle, measuring horizontally or perpendicularly to the bottle axial line. Thus this ring appears to be a true ring when looking downward along the axial line of the bottle, as shown in Fig. 2. But the slant given to this ring with this exterior form makes it slightly elliptical, as shown in Fig. 4. Yet this form is so nearly circular as to still adapt the ring to receive the ordinary disc-form or circular sheet metal crown and allow the crimped flange, E¹, of the crown to extend over and engage the ring, as shown in Figs. 6 and 7.

If the locking ring were thus slightly elliptical and also horizontal, the disc-form or circular crown would, when secured on the ring, extend farther over the parts of the ring which are cut by the shorter ring axis than over the parts cut by the longer ring axis. But the high part of the crown flange

takes a higher position against the inner face of the die, F. The interior of the die is circular in cross section and tapers from the lower end upward. Therefore the upper part of the crown flange is crimped to a greater degree than at other parts. But practice has shown that this inequality in crimping may exist and the crown be amply secured to the ring. Since all parts of the exterior lateral face of the slanting locking ring are equi-distant from the axial line of the bottle measuring horizontally or perpendicularly to the bottle axial line, whereby that ring appears to be a true ring when looking downward along the axial line of the bottle, as already herein described, the die, F, can, by downward movement parallel to the axial line of the bottle, engage the rim of the cap to press said rim downward over all of the external lateral face of said ring, as above described in connection with Fig. 6 of the drawings. Thus my improved bottle is adapted to receive the cap or crown blank by means of the ordinary cap delivering mechanism, and the cap may then have its rim folded on the locking ring by means of automatic machines now in use for that purpose.

For opening the bottle, this crown is to be removed in the usual manner by means of any tool adapted to engage and bend parts of the crown flange outward.

By reference to Fig. 8, the action during drinking from my improved bottle will be seen. The bottle is placed horizontally with the neck a little higher than the base of the bottle and with the high part (now the low part) of the locking ring, D, resting against the lower lip of the person, space being left between the upper lip of the person and the bottle for the passing of the liquid. This leaves the locking ring leaning away from the upper lip and the nose so as to leave a clear passage from the atmosphere through what is now the upper part of the mouth of the bottle. Thus air can freely flow along the course indicated by the arrow to take the place of liquid flowing from the bottle. While the drinking proceeds, the bottle is to be gradually tilted upward to allow all of the liquid to discharge. But this tilting need be only high enough to bring what is then the low part of the wall of the neck of the bottle to or slightly above the horizontal position.

I claim as my invention,

1. A bottle having an elongated body and a neck and a mouth whose axial line coincides substantially with the axial line of the bottle, the lip of the mouth being slanting.

2. A bottle having an elongated body and a neck and a mouth whose axial line coincides substantially with the axial line of the bottle, the lip of the mouth being slanting and elliptical.

3. A bottle having an elongated body and

- a neck whose axial line coincides substantially with the axial line of the body and a slanting locking ring on said axial line. 10
4. A bottle having an elongated body and a neck on the axial line of the body and the neck having an elliptical slanting locking ring whose axial line coincides substantially with said axial line. 15
5. A bottle having an elongated body and a neck on the axial line of the body and the neck having an elliptical slanting locking ring whose axial line coincides substantially with said body axial line and said locking ring having all parts of its outer face equidistant from said body axial line, measuring on lines which are perpendicular to said axial line. 20
6. A bottle having an elongated body and a neck on the axial line of said body, and said neck having a slanting locking ring whose axial line coincides substantially with said body axial line, and said neck having a holding ring, the lower part of which is in a plane to which said body axial line is perpendicular. 25
7. A bottle having an elongated body and a neck on the axial line of said body, and said neck having a slanting locking ring on said axial line, and said neck having a holding ring, the lower part of which is in a plane to which said axial line is perpendicular and the upper part of the holding ring being parallel with the locking ring. 30
8. A bottle having an elongated body and a neck on the axial line of said body, and said neck having a slanting locking ring whose axial line coincides substantially with said body axial line, and said neck having a holding ring, the lower part of which is in a plane to which said body axial line is perpendicular and the holding ring being externally rounded in upright section. 35
9. A bottle having an elongated body and a neck and a mouth whose axial line coincides substantially with the axial line of the bottle, the lip of the mouth being slanting, and a crown fitted to the slanting locking ring. 40
10. A bottle having an elongated body and a neck and a mouth whose axial line coincides substantially with the axial line of the bottle, the lip of the mouth being slanting, and a circular crown resting on the slanting locking ring and having its edge crimped over said ring. 45
11. A bottle having an elongated body and a neck on the axial line of said body and having a slanting locking ring whose axial line coincides substantially with said axial line, and a crown resting on and making unequal engagement with said ring. 50
12. The herein-described method of crowning a bottle having an elongated body and a neck on the axial line of said body and said neck having a slanting locking ring whose axial line coincides substantially with said
- axial line, which method consists in placing over said ring a circular crown blank and then crimping the edge of said blank onto the locking ring by pressure on the rim of said blank toward said body and parallel to said body axial line and obliquely to the plane of said blank. 55
